United States Patent

Des. 237,767
Patented Nov. 25, 1975

237,767

SOAP HOLDER

Horst Gruendler, 15230 Hackberry Lane,
Brookfield, Wis. 53005

Filed May 20, 1974, Ser. No. 471,695

Term of patent 14 years

Int. Cl. D23—02

U.S. Cl. D6—89

FIG. 1.

FIG. 2.

FIG. 1 is an enlarged perspective view of a soap holder showing my new design; and

FIG. 2 is a perspective view thereof, taken from the side opposite that shown in FIG. 1.

I claim:

The ornamental design for a soap holder, as shown.
